UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

CLOSING DEVICE FOR GUNS HAVING MULTIPLE BARRELS.

Application filed June 9, 1921. Serial No. 476,303.

To all whom it may concern:

Be it known that I, EUGÈNE SCHNEIDER, a citizen of the République of France, residing at 42 Rue d'Anjou, Paris, France, have invented new and useful Improvements in or Relating to Closing Devices for Guns Having Multiple Barrels, which is fully set forth in the following specification.

This invention has for its object to provide an improved closing device for guns having multiple barrels carried by a common sleeve, and comprising one or more breech blocks (breech screws or wedges) less in number in any case than the number of the tubes, these blocks being movable so that the closing can be effected at will for firing with any one of the gun barrels.

The characteristic features which are common to the various closing devices of this kind, as described and illustrated in the accompanying drawings, consist on the one hand in such a construction of the breech block or blocks that the latter are able to rotate or rock around the symmetry axis of the group of gun barrels or around an axis situated in the symmetry plane of the said group. The characteristics consist also on the other hand of one or more firing mechanisms grouped around the said axis or so arranged as to be capable of turning around the said axis in such a manner as to always act radially in relation to the gun barrels irrespectively of whichever breech block is being used, whilst in all cases being operated by the action in one and the same sense of a common firing lanyard, so that only the hammer corresponding to the loaded gun barrel is able to operate.

The invention comprises, further, various other characteristic features hereinafter described in detail.

Figs. 1 to 9 inclusive illustrate a first constructional form of the invention.

Fig. 1 is a longitudinal elevation, partly in section, of the general arrangement of the gun.

Fig. 2 is a section on the line 2—2 of Fig. 1.

Fig. 3 is a rear detail elevation partly in section drawn to a larger scale.

Fig. 4 is a section on the line 4—4 of Fig. 3 showing the breech block in position for closing one of the gun barrels carried by the common sleeve.

Figs. 5 and 5^a are corresponding sections

showing the same breech block in one of the positions it occupies during the run out of the gun.

Fig. 5^b is a detail of the head against which the spring acts.

Fig. 6 is a detail elevation of the plate for engaging a cartridge case.

Fig. 7 is a partial developed plan of the mechanism for rotating around the symmetry axis of the group of tubes.

Fig. 8 is a sectional elevation on the line 8—8 of Fig. 7.

Fig. 9 is a section on the line 9—9 of Fig. 3.

Figs. 10 to 14 inclusive illustrate a constructional example in which the gun comprises two gun barrels carried by a common sleeve, with a breech block (shown as a breech-screw in the example) movable around an axle-pin situated in the symmetry plane of the two gun barrels, in such a manner as to be capable of being caused to serve as a breech block for one or the other of the two gun barrels alternately.

Fig. 10 is a rear elevation showing the breech block engaged in the right-hand gun barrel;

Fig. 11 is a section through the common sleeve on the line 11—11 of Fig. 10;

Fig. 12 is a rear elevation, partly in section, showing the breech-screw which has been turned around its axle-pin in the return of the gun into battery position and has been moved out of the way to allow the said gun barrel to be reloaded:

Figs. 13 and 13^a are longitudinal elevations corresponding to Fig. 12, partly in section, through the sleeve on the line 13—13 of Fig. 12;

Fig. 14 is a partial section on the line 14—14 of Fig. 13.

Figs. 15 to 18, inclusive, illustrate a constructional form in which a common sleeve A carries four gun barrels, the gun comprising only two breech blocks which are connected together in such a manner as to rock around the symmetry axis of the group of the four gun barrels, each of these breech blocks serving alternately to close a different gun barrel, while the whole comprises only one firing hammer.

Fig. 15 is an end elevation of the gun;

Figs. 16 and 17 are sections respectively on the lines 16—16 and 17—17 of Fig. 15;

Fig. 18 is a partial section showing the

firing hammer shifted for the purpose of using it for firing with the left-hand group of the gun tubes, whereas in Figs. 15 to 17 it is shown arranged for firing the right-hand group of gun barrels.

Figs. 19 to 22, inclusive, illustrate a modification of the constructional form illustrated in Figs. 15 to 18.

Fig. 19 is a partial end view;

10 Figs. 20 and 21 are sections respectively on the lines 20—20 and 21—21 of Fig. 19;

Fig. 22 is a partial developed section on the line 22—22 of Fig. 19.

15 Figs. 23 to 27, inclusive, illustrate a constructional form in which four gun barrels are carried by a common sleeve A, comprising a breech block that is adapted to close simultaneously all four barrels of which any one can be loaded at will, the 20 breech block serving as a support for four strikers (one for each gun barrel) and carrying four corresponding firing hammers adapted to be operated by means of a common firing lanyard. The closing of the 25 breech is, however, only possible if one only of the barrels is loaded, and the corresponding firing hammer alone can be brought into operation.

Fig. 23 is a rear elevation showing the 30 breech closed;

Fig. 24 is a sectional plan on the line 24—24 of Fig. 23;

Fig. 25 is a sectional plan showing an intermediate position of opening or closing 35 of the breech;

Fig. 26 is a sectional plan similar to that of Fig. 24, showing the breech open, or, more strictly speaking, after it has been unscrewed from the breech-nut and has 40 been swung around the axis of its pivotal connection to the sleeve;

Fig. 27 is a section on the line 27—27 of Fig. 24.

45 Figs. 28 to 30 illustrate a constructional form wherein two superposed gun barrels A¹, A² are carried by a common sleeve A.

Fig. 28 is a rear elevation;

Fig. 29 is a section on the line 29—29 of Fig. 28;

50 Fig. 30 is a developed circular section taken on the line 30—30 of Fig. 28.

Referring to Figs. 1 to 9, inclusive, the improved gun comprises four tubes or gun barrels A¹, A², A³, A⁴ carried by a common 55 breech sleeve A. These four tubes are arranged symmetrically around a common axis a, the sleeve together with the four tubes, being carried by a common slide B which slides in the usual manner on the 60 cradle C.

In this example one and the same breech block D constructed in the form of a breech screw is arranged in such a manner as to be capable, after it is passed out of one of 65 the breech nuts a¹ formed in the sleeve A,

of receiving an angular movement around the symmetry axis a so as to be capable of engaging in the adjacent breech nut a², and successively in the breech nuts a³, a⁴ of the group of gun barrels.

As will be hereinafter seen, the successive displacements of the breech block D through 90° around the axis a are effected automatically during the run out of the gun.

For the purpose of this automatic rotation, the breech screw D is mounted on an arm E which is fixed on a rod F arranged along the symmetry axis a, and journalled at its rear end in a bracket G which is adapted to slide on the guiding slideways c 80 of the cradle C.

The rod F has at its front end a head F¹ guided by four studs f in straight grooves H¹, H², H³, H⁴, formed in a tube H which is supported at its rear end in the sleeve A 85 and at its front end in a collar I that forms a support for the chases of the four gun barrels; the sleeve A and the collar I being supported in the known manner by the slide B.

The grooves H¹, H², H³, H⁴ are connected two-by-two at an intermediate point of their length by means of helical grooves h¹, h², h³, h⁴. At the points of intersection of the helical grooves and the straight grooves, 95 spring tappets J, K are arranged respectively in the straight grooves and the helical grooves. Each tappet J has in front a guiding surface j as a prolongation of the helical groove into which it opens and at the 100 rear an inclined surface j¹ the bottom point of which is normally flush with the bottom of the rear branch of the said groove wherein the said tappet is arranged.

Each of these tappets K has at its rear a 105 guiding surface k as a prolongation of the rear branch of the straight groove into which it opens, whereas in front it has an inclined surface k¹, the bottom point of which is normally flush with the bottom of the helical inclined surface where the said tappet is arranged.

The rod F is held by means of two collars f which prevent it from moving longitudinally in relation to the bracket G. It 115 has an eyelet F² for the guidance of the cord L that serves to actuate the firing hammer M carried by a pin m journalled in a bracket E fixed to the arm E.

The breech screw D has in the known 120 manner a central portion D¹ whereof the screw threads d¹ of very steep pitch are adapted to work in a corresponding thread e tapped in a nut formed in the arm E.

Assuming the breech screw D having its 125 interrupted threads engaged in the breech nut a¹ corresponding to the gun barrel A¹, as shown more particularly in Figs. 3 and 4, the action of the recoil after the shot is fired, will cause a movement of the four gun 130

barrels, sleeve A and bracket G together to the rear. In the recoil movement, the bracket G will strike the inclined surface n of a spring bolt N mounted in the cradle, 5 (Figs. 3 and 9). It will force this bolt out of the way and will strike the surface n^1 of the latter immediately at the beginning of the run out movement.

The bracket G is thus held in the position 10 shown in Fig. 5, but the gun barrels and the sleeve A continue together to be returned to the firing position by the usual recuperator (not shown), this movement producing, in the known manner, an unscrewing of the 15 screw D by rotation of the central portion D¹ in the nut e.

The run out movement of the gun barrels continues until the front edge of the cartridge case O has become disengaged.

20 During this time the studs f¹ of the rod F have remained behind with the latter, whereas the front portions of the straight grooves H¹, H², H³, H⁴ advances relatively to the studs. Immediately the rear ends of 25 the forward branches of the straight grooves have moved (as shown in Fig. 7) past the studs f¹ that have remained stationary, the tappets J will strike these studs with their surfaces j thereby compelling the rod F to 30 turn whilst the studs are guided in the helical grooves h¹, h², h³, h⁴ which continue their forward movements; the tappets K move out of the way under the studs f¹ which they strike with their inclined surfaces k¹. During all these movements the 35 spring F³ coiled around the rod F is stressed. The gun tubes and sleeve A complete their run out movement, whilst the rear branches of the straight grooves H¹, H², H³, H⁴, slide 40 over the studs f¹. In the meantime the rotational motion of the rod F has brought the axis of the breech screw D into the prolongation of the axis of the gun barrel A². The empty cartridge case O is then removed 45 by hand and replaced by a cartridge which is held in the known manner in a plate P. This plate, according to this invention is loose in the breech screw D so that it can always be turned by hand so as to bring to 50 the upper position the portion p, that has no clip, for engaging the rim of the cartridge case.

If now the bolt N be disengaged from the bracket G, the latter will be moved forward by the expansion of the spring F³. The rod F is returned to the front, and its studs f¹ slide freely in the straight grooves H¹, H², H³, H⁴ and in their progress simply move the tappets J out of the way.

55 Towards the end of the run out movement the breech screw D engages behind the cartridge which it carries, in the chamber a², the plain sectors of the screw being brought opposite the threaded sectors of the breech 60 nut. The spring bolt Q which was engaged

in a socket in the nut e meets with its beak q the inclined surface r² of a heel R² which compels the bolt to rise; the screw D thus becomes free.

The arm E in continuing its forward 70 movement with the bracket G causes the screw to rotate by means of the nut e, and assures in the known way the closure of the breech.

Three of the breech nuts are always covered up when they do not serve for firing. For this purpose a disc S is guided in the engaging heels R¹, R², R³, R⁴. This disc is pierced with an aperture for the free passage of the screw D. It is fixed on the rod 80 F by means of a key s which is adapted to slide in a groove F⁴ formed in the said rod.

Referring to Figs. 10 to 14, inclusive, the two gun barrels A¹, A² which the gun comprises are arranged symmetrically in relation 85 to the longitudinal axial plane a in the common sleeve A, the sleeve and the gun barrels being together carried by a common slide B sliding on a cradle C.

In this example it has been assumed, as 90 in the preceding example, that the breech block D is of the well known type with interrupted screw threads engaging in the corresponding threads of a nut (a¹ and a² alternately) formed in the sleeve A.

The breech screw works exactly as in the preceding example in a nut e provided in an arm E whose hub is in this case loose on a rod F situated in the axial plane a, parallel to the axes of the gun barrels A¹ and A² 100 and provided with a head F¹ for guidance in a tubular recess H of the sleeve A. A spring F³ coiled around the rod bears at one end against the head F¹, and at its other end against the bottom of the recess H.

The arm E carries a finger T provided at its free end with a cylindrical tail t movable in a spherical member t¹ mounted in a roller T¹ which is engaged in its turn in a slideway T² formed in a part which can be caused to 110 revolve by means of a trunnion t² in a bearing B¹ formed on the slide B, in such a manner as to bring the open front end of the said slideway alternately in front of one or other of the two slideway sections B² or 115 B³ formed in the slide B.

According as, by means of a spring handle T³, the slideway T² is moved until the reduced portion of handle T³ is engaged in one or the other of the two sockets b² or b³, 120 the said slideway will occupy the position shown in Fig. 11 or an inverse symmetrical inclined position, indicated in dot-and-dash lines in Fig. 13. In the first case the slideway T² connects with the slideway section 125 B² and in the second case it connects with the slideway section B³.

The parts being in the position indicated in Figs. 10 and 11, it will be perceived that the breech being closed by the engagement 130

of the breech screw in the chamber a^1 of the gun barrel A^1 , the roller T^1 will be situated at the bottom of the fixed slideway B^2 to which there connects the pivoted slideway T^2 whose spring bolt T^3 is engaged in the socket b^2 .

On the recoil of the gun barrel a tappet F^5 , carried by a guide rod F , moves out of the way by its lower end a spring bolt N 10 mounted in the cradle C . On the run out movement the tappet F^5 abuts against the surface n^1 of the said bolt whereby the rod F and with it the arm E are stopped, whereas the sleeve A and the barrels A^1 and A^2 15 continue their forward movement, as also do the fixed slideways B^2 , B^3 and the pivoted slideway T^2 . The forward movement of the sleeve A produces, as in the preceding example, an unscrewing of the breech screw D by 20 the rotation of the nut e of the arm E .

During this time the roller T^1 changes its position in the groove B^2 . The gun barrel continuing its forward movement, the breech screw D will be entirely disengaged and 25 withdrawn from the chamber a^1 ; by means of the hooks d^2 it has moved with it the rim of the empty cartridge case O . The sleeve A , still continuing its forward movement, the inclined portion T^2 of the guide slideway will engage the roller T^1 thereby causing 30 a rotation of the finger T and consequently also of the arm E around the rod F which has remained stationary. The hooks d^2 move to one side out of the way together 35 with the breech screw D and release the cartridge case O which can then be withdrawn by hand. If it be desired to continue firing with the gun barrel A^1 a fresh cartridge is placed in the said barrel. There- 40 by, the spring bolt N is moved out of the way so as to allow the spring F^3 which has been stressed during the run out movement to become unstressed. Since, at this moment the slideway T^2 — B^2 is stationary, the 45 roller T^1 which moves, produces a rocking of the arm E which has the result of first bringing the breech screw D in front of the chamber a^1 . Whilst the roller T^1 is moved through the section B^2 of the slideway, the 50 breech screw enters its lodgment and the hooks d^2 , by engaging in the recesses a^5 , grip the rim of the cartridge. As in the fore- 55 going example, the continuation of the return movement of the rod F causes the screw E to rotate on its nut e and, at the same time, causes the screw threads of the breech screw to engage the screw threads of the nut a^1 .

If, when the parts are in the position 60 shown in Fig. 13, when the gun has returned into firing position it is desired to fire with the barrel A^2 , it is sufficient to disengage the spring bolt T^3 from the socket b^2 and to cause the slideway T^2 to pivot in such a 65 manner as to engage the said bolt in the

socket b^3 . In this movement the roller, T^1 , and consequently the arm E and the screw D are carried along; thus the screw assumes a position symmetrical to its starting position relatively to the axial plan a , and is thus 70 in the desired position to engage in the chamber a^2 after the bolt N shall have been moved out of the way. The firing mechanism is constructed exactly in the same manner as in the foregoing example. 75

In the embodiment illustrated in Figs. 15 to 18, inclusive the breech blocks are of the wedge type. Two blocks U , U^1 are guided by ribs u , u^1 in correspondingly shaped guides in the sleeve A and are connected together in such a manner as to be brought alternatively, the one U in front of the chambers a^1 and a^2 whilst the other breech block is brought alternatively in front of the chambers a^3 , a^4 . The connection of the two breech blocks is effected by means of a common operating lever E whose axis of oscillation E^2 coincides with the symmetry axis a of the group of gun barrels. The lever E is engaged by means of rectangular slideways E^3 on square slide blocks V , V^1 in which there is adapted to turn an axial cylindrical projection U^2 of the corresponding breech block, which projection serves at the same time as a guide for the 85 striker Z .

The axle pin m on which is fixed the single firing hammer M is journalled in a bearing E^4 projecting from the lever E and in a sheath E^5 that is likewise fixed to the said lever. On the axle pin m is fixed a pinion m^1 which is adapted to mesh alternately with one or other of the two opposed racks W^1 , W^2 cut on or carried by a slide block W to which the firing lanyard L is attached 100 which passes through an eyelet e^1 of the lever E . The slide block W is adapted to move in a sleeve X which is itself movable in the sheath E^5 , the movements of the said slide block being limited by two collars w , w^1 of which one serves as an abutment for one end of a spring w^2 that bears with its other end against the sleeve X . 110

As shown in Figs. 15, 16 and 18, the slide block W and the sleeve X are pierced with 115 apertures that allow of their movement along the axle pin m which extends through them. A spring bolt X^1 fitted in the sheath E^5 is adapted to engage in one or the other of two sockets x or x^1 formed in the sleeve X for fixing the latter upon the lever E in one or other of the two positions shown respectively, the former in Figs. 15 and 16 and the second position in Fig. 18. 120

The parts are arranged as shown in Figs. 125 15 to 17, for firing at will either with one or other of the right hand gun barrels A^1 , A^2 . The lower barrel A^2 can be loaded during the time that the upper barrel A^1 is closed. 130

Firing is effected with the upper barrel A¹, the firing being effected by pulling the lanyard L downwards, the pinion m^1 meshing with the rack W¹ of the slide block W, and thus receiving a rotational movement that moves the hammer M away, whilst the spring w^2 is compressed. The release of the lanyard L causes the expansion of the spring w^2 and the movement in the reverse direction of the rack W¹, and causes the hammer M to be impelled against the striker M¹. After the shot has been fired and the gun returned to the firing position, the lever E is operated in such a manner as to 10 depress the breech block U and bring it in front of the lower barrel A². In the descent of the breech block a boss u^2 acts upon a small lever y fixed on the axle pin Y carrying the extractors Y¹, thereby actuating the latter which causes the cartridge case O to move partially out of the chamber a¹. On the other hand, two chamfers u^3 , u^4 are formed on the block U, the lower chamber u^4 serving for forcing into the chamber 20 a² the cartridge O¹ which has been previously engaged therein. In other words, the sliding movement of the block U, produces the opening of the upper barrel A¹ and the closing of the lower barrel A², at the same time as the extraction of the empty 30 cartridge case O and the forcing in of the cartridge O¹. Once the lower cartridge case O¹ has been withdrawn, it is sufficient to operate the lever E in the reverse direction in order to return the block U into the position shown in Figs. 15 and 17 after a fresh cartridge has been engaged in the chamber a¹.

If, for the purpose of allowing the right 40 hand gun barrels to cool and to have a rest, it is desired to fire with the left hand gun barrels, A³, A⁴, it will be sufficient to disengage the bolt X¹ from the socket x, and by an operation of the hammer M, to bring the 45 socket x¹ opposite the said bolt. The rotation of the said hammer in the direction of the arrow (Fig. 16) effects the movement of the rack W² and the carrying along of the sleeve X by the slide block W. In short, the 50 parts are brought into the position shown in Fig. 18. The hammer M is thus so situated as to be capable of firing the gun, either with one or the other of the two gun barrels A³, A⁴; the operation being, by the way, 55 exactly the same as that just hereinbefore described.

It is advisable to note that the operation of the blocks U, U¹ is effected by means of the lever E without appreciable effort because the two blocks balance each other.

In the embodiment illustrated in Figs. 19 to 22, inclusive, the gun comprises, as in the foregoing example, four gun tubes and two breech blocks U, U¹ arranged diametrically 65 opposite one another. But in this arrange-

ment the blocks are formed of cylindrical segments that are held by means of teeth u^5 in corresponding cylindrical grooves a^6 of the sleeve A. These two blocks fixed to each other are thus able to revolve around the symmetry axis a, the upper block U serving for firing alternatively with one or the other of the two upper gun tubes A¹, A², whereas the block U¹ will serve to fire alternatively one or the other of the lower gun tubes A³, A⁴. The rocking movement of the blocks which balance each other is effected by the operation of a handle U³. For firing alternatively with the gun barrels A¹, A², the handle U³ is bolted alternatively in one or the other of two sockets a⁷, a⁸ wherein the bolt u^6 engages which is jointed to one of the arms of a rocking beam U⁴ that is actuated by a spring stud U⁵.

The handle U³ carries a guide eye u^7 for the firing lanyard L. The firing mechanism is identical with the one described in the foregoing example.

The parts being in the position shown in Figs. 19 and 20, the gun is fired by operating the lanyard L. After the shot has fired and the gun returned to the firing position, the handle U³ is moved in a counter-clockwise direction after the bolt U³ has been moved inwards so as to disengage the bolt u^6 from the socket a⁷. The two balanced blocks revolve by the displacement of the teeth u^5 in the grooves a^6 . The rotational motion of the blocks may be arrested by a stud but is automatically limited by the engagement, 95 in the socket a⁸, of the bolt u^6 that is released by the operator. This movement produces, as in the foregoing example, the extraction of the empty cartridge case O and the insertion of the live cartridge O¹ into the 100 chamber a². The extractor fork Y is actuated by the pressure that is exerted upon a finger y by an inclined surface u^9 formed on an axial projection of the metal mass connecting together the two blocks U, U¹. The 105 insertion of the cartridge O¹ is assured by the connection of an inclined surface u^8 upon the rim of the said cartridge.

If, for the purpose of giving the gun tubes, A¹, A² a rest, it is desired to fire 115 alternatively with the tubes A³, A⁴, it will be sufficient as in the foregoing example, to cause the firing hammer to turn through 180° whereby it is brought into the desired position for firing through the breech block 120 U¹ which is brought alternatively in front of the gun barrel A³ or A⁴ by the operation of the handle U³.

In the example shown in Figs. 23 to 27 inclusive, the breech block D which is common 125 to the four gun barrels is assumed to be of the known type with interrupted threads, and operable by means of a lever E pivoted on an axle pin E⁶ journalled in the sleeve A. The block D comprises in the known manner 130

screw-threaded sectors d^3 interrupted by plain sectors d^4 . To these screw-threaded sectors and plain sectors there correspond respectively screw-threaded sectors a^{10} and 5 plain sectors a^9 of the breech nut. The block D is held constantly in a holder E⁷ which is pivoted like the lever E around the axle pin E⁶. During its rotational motion the lever E moves, by means of a tenon e², a slide 10 block E⁸ guided in the holder E⁷ and to which longitudinal motion is imparted. This slide block meshes by means of teeth e⁸ with a toothed sector d⁵ formed on the breech screw D. Therefore, in the movements 15 which it receives from the lever E, the said slide block assures the screwing and unscrewing of the breech screw into and out of the breech nut. When the unscrewing is completed the lever E, holder E⁷, slide block 20 E⁸ and the breech screw D, carried along by a spur e⁶ revolve together as a whole around the axle pin E⁶ for withdrawing the breech screw out of its lodgment in the gun barrel. In a word, the breech block which is common 25 to the four gun barrels is constructed identically the same as a breech block for a single gun barrel of the type above referred to, the opening and closing being effected simultaneously with the common block for 30 all four gun barrels at once. The block D is, of course, pierced with four passages which, when the breech is closed, are situated in the prolongation of the axes of the four gun barrels; each of these passages serving as a 35 lodgment for a striker (Z¹, Z², Z³, Z⁴).

According to this invention a firing hammer for each gun barrel is pivoted to the holder E⁷ in a bracket carried by the latter in such a manner that the hammer shall be 40 able to act upon the corresponding striker when the breech is completely closed. The four hammers are so arranged that they can be operated by means of a common firing lanyard L guided in an eye e¹ provided in the holder E⁷. One of the ends of this lanyard is attached to a lever L¹ which is likewise pivoted to the holder E⁷ and carries a pinion L². This pinion meshes with a rack 45 2 formed on a slide block I guided along the axis of the breech block D in the latter and in the holder E⁷.

The slide block I is thus actuated, each time the lanyard L is pulled, by a spring 3 bearing at one end against the bottom of the 55 slide block and at its other end against a stud d⁶ projecting inwardly in the block D, said spring having a constant tendency to move the said slide block outwards. The operation of any one of the hammers by 60 means of the firing lanyard can take place only when an engagement has been produced between the said hammer and the slide block I. This engagement is effected by the action of a part set in motion by its 65 meeting with the base of a cartridge inserted

in position, and only when the breech is completely closed.

The engaging part consists, for each hammer, of a finger 4 projecting from a flexible strip 5 guided in the slide block I. This strip is provided at its outer end with a rack 6 meshing constantly with a toothed sector 7 formed on the corresponding hammer.

Owing to the tension of the strip, the finger 4 is moved outwards, and inversely it 75 can be pushed into a corresponding notch 8 formed in the slide block I by the action of a spring pusher 9 guided in the breech block D. The nose 10 of this pusher is movable in a guide d⁷ formed in the stud d⁶. A chamfered nose 11 on the said pusher is engaged normally in a notch 12 of corresponding shape formed in a spring stud 13 lodged in the breech block D; one end 14 of which stud normally projects in front of the inner 85 end surface of the said block.

When the breech is open, the parts of this quadruple firing mechanism occupy the position shown in Fig. 26. The strips 5 of the fingers 4 bear against the sides of the 90 recess formed in the breech block, a nipple 15 projecting outwardly from each strip being engaged in a groove 16 of the block D. The springs of the pushers 9 are unstressed and the noses 11 are engaged in the 95 notches 12 of the spring studs 13-14; all the stops 14 project from the front end surface of the breech block.

If the gun is correctly loaded with only one cartridge placed, for instance, in the 100 gun barrel A¹, the breech may be closed completely by the usual operation of the lever E. The corresponding stop or stud 14 will then alone encounter the obstacle 105 constituted by the base of the cartridge case O; it will be pushed outwardly, forcing back, in its turn, the corresponding pusher 11-9-10, the nose 10 of which will be able to engage freely in the groove of the stud d⁶ as shown in Figs. 24 and 27. 110 The spring of the pusher is compressed, and the finger 4 of the corresponding strip 5 engages in the recess 8 of the slide block I, and the engagement between the strip 5 and the said slide block will thus be effected, 115 whilst the three other strips remain in the positions they occupy in Fig. 26. If, therefore, the firing lanyard L be actuated the latter will move, by means of the lever L¹ and the pinion L², the slide block I which 120 will carry with it solely that one of the strips 5 which is engaged, whereas it will slip over the three other strips.

The longitudinal displacement of the rack 6 fixed to the actuated finger 4 produces 125 the rotation of the corresponding hammer. When the operator releases the firing lanyard, the expansion of the spring 3 which was previously compressed, assures the propulsion of the hammer against the striker. 130

It will be perceived that, if inadvertently cartridges have been placed in more than one gun barrel it will be impossible to close the breech. If, for instance, it be assumed that cartridges have been placed into the two right hand gun barrels or into the two left hand gun barrels, the corresponding stops 14 will strike simultaneously the bases of the cases of these cartridges, and their noses 10 will engage simultaneously in the corresponding branch of the two grooves formed at right angles to each other in the stud d^6 . One of the stops only will be able to come into the operative position shown in Fig. 27 and engage a corresponding finger in the slide block I, whilst the other stop 14 will therefore remain projecting and, by its abutment against the base of the corresponding cartridge, will prevent the completion of the closing of the breech.

If it be supposed that two gun barrels on the same level have been loaded, for instance the upper gun barrels or the lower gun barrels, then noses 10 of the opposite stops will be actuated at the same time, and neither one nor the other will be able to engage completely in the groove of the stud d^6 thus rendering it impossible for the two studs 14 to move completely out of the way.

In the embodiment illustrated in Figs. 28 to 30 inclusive, the breech block D which is common to the two gun barrels, is guided by means of circular teeth in corresponding grooves in the sleeve A. This breech block comprises a recess D^2 which comes opposite the upper gun barrel A² whilst an axial passage, containing a striker Z, is brought into the axis of the diametrically opposite lower gun barrel A¹.

The breech block D can be operated by means of a lever E whose hub is pivoted so as to swing around an axle pin E² projecting from the centre of the sleeve A.

As in the foregoing examples, the lever comprises an eye e¹ for guiding the firing lanyard L. As in the known breech mechanisms of this type, the firing hammer is carried by a pin journalled in a bracket fixed to the breech block D. However, the lever E, instead of being fixed to the breech block, is connected to the latter by a step-down gear in such a manner that it will make only one fourth of a revolution whilst causing the breech block D to make one half of a revolution for using alternatively one or the other of the two gun barrels A¹, A².

On the block D there is fixed for this purpose a pinion D³ meshing with a second pinion D⁴ loose on axle D⁵ carried by arm D⁶ fixed to the axle E². The pinion D⁴ meshes on the other hand with a toothed sector E⁹ having a diameter double that of the pinion D³ and fixed to the lever E.

The device for effecting the extraction of

the empty cartridge case and the loading of the fresh cartridge at the moment of closing the breech, is of the known type. The breech block D being formed, as shown in Fig. 30, with two inclined surfaces D¹⁰ for forcing 70 home the fresh cartridge and a boss D¹¹ acting on the extractor fork Y.

I claim—

1. A breech mechanism for guns having multiple barrels carried by a common sleeve, 75 comprising a control arm, one or more breech blocks secured to said arm in such a manner that the same may be moved thereby about the symmetry axis of the group of barrels to serve alternately for closing one 80 or another of said barrels, firing means carried by each block, and a lanyard guided in said arm for actuating said firing means.

2. A breech mechanism for guns having multiple barrels, comprising a control arm, 85 one or more breech blocks secured to said arm whereby the same may be rotated to alternately close one or more of said barrels, firing means for each block, and a lanyard guided in said arm for actuating said firing 90 means.

3. In a device of the class described, a breech-block control arm, one or more breech blocks secured to said arm for closing one or another of a plurality of barrels, firing 95 means carried by each block, a lanyard for actuating said means, it being possible to fire only the particular gun barrel which the gunner actually desires to fire, and means actuated by movement of each block 100 for extracting a cartridge from any one of said barrels.

4. A breech mechanism for a gun having a plurality of barrels carried by a common sleeve, comprising, in combination, a control arm, a breech-closing member carried by said arm and movable about the symmetry axis of said barrels by means of said arm, means actuated by movement of said member for positively ejecting a cartridge case from any one of said barrels, firing means carried by said member, and a lanyard guided in said arm for actuating said last-named means. 105

5. A breech mechanism for guns having a plurality of barrels, comprising a breech-block control arm pivoted in the symmetry axis of said barrels, a breech block carried by said arm whereby said block may be moved to close one or another of said barrels, firing means carried by said block, and a lanyard for actuating said means. 115

6. A breech mechanism for guns having a plurality of barrels, comprising a breech-block control arm, a breech-block carried by said arm, means for automatically moving said block to alternately close any one of said barrels, firing means carried by said block, and a lanyard for actuating said last-named means. 125

7. A breech mechanism for guns having four barrels carried by a common sleeve, comprising a breech-block control arm, a breech block carried by said arm, means for automatically moving said block to alternately close any one of said barrels, firing means carried by said block, and a lanyard for actuating said last-named means.
8. A breech mechanism for guns for multiple barrels carried by a common sleeve, comprising, in combination, breech-closing mechanism, a control arm connected to said

mechanism and operating to move the same about the symmetry axis of the group of barrels to alternately close said barrels, firing 15 means for said mechanism, and a firing lanyard guided in said arm for moving said firing means.

In testimony whereof I have signed this specification.

EUGÈNE SCHNEIDER.
